(57) **CLAIM**

The ornamental design for an ankle case holder, as shown and described.

DESCRIPTION

FIG. 1 is a top perspective view of the ankle case holder, showing my new design;

FIG. 2 is a bottom perspective view thereof;

FIG. 3 is a front view thereof;

FIG. 4 is a left side view thereof;

FIG. 5 is a right side view thereof;

FIG. 6 is a rear view thereof;

FIG. 7 is an above view thereof;

FIG. 8 is a bottom view thereof;

FIG. 9 is a fastened top perspective view thereof;

FIG. 10 is a fastened bottom perspective view thereof;

FIG. 11 is a fastened front view thereof;

FIG. 12 is a fastened left side view thereof;

FIG. 13 is a fastened right side view thereof;

FIG. 14 is a fastened rear view thereof;

FIG. 15 is a fastened above view thereof;

FIG. 16 is a fastened bottom view thereof; and,

FIG. 17 is an in-use top perspective view thereof.

The broken lines illustrate environmental structure of the ankle case holder that forms no part of the claimed design.

1 Claim, 11 Drawing Sheets
